UNITED STATES PATENT OFFICE

143,157

DESIGN FOR A VANITY CASE

Peter Muller-Munk, Pittsburgh, Pa., assignor to Illinois Watch Case Co., Elgin, Ill., a corporation of Illinois

Application September 12, 1945, Serial No. 122,043

Term of patent 7 years

(Cl. D86—10)

To all whom it may concern:

Be it known that I, Peter Muller-Munk, a citizen of the United States, residing at Pittsburgh, in the county of Allegheny and State of Pennsylvania, have invented a new, original, and ornamental Design for Vanity Cases, of which the following is a specification, reference being had to the accompanying drawing, forming part thereof, wherein:

Fig. 2 is a bottom plan view thereof;

Fig. 3 is an elevational view of the rear face thereof; and

Fig. 4 is an elevational view of one side face thereof.

I claim:

The ornamental design for a vanity case, as shown.

PETER MULLER-MUNK.
